WHEELED CLOTHES SUPPORT

Floyd R. Barbee, 5716½ N. Charlotte St.,
San Gabriel, Calif. 91776

Filed Dec. 26, 1967, Ser. No. 9,930

Term of patent 14 years

Int. Cl. D6—01

U.S. Cl. D33—8

Fig. 1

FIG. 1 is a perspective view of a wheeled clothes support showing the new design including a wheeled support therefor;

FIG. 2 is a top plan view of the design article showing the clothes support rod in the extended form thereof;

FIG. 3 is a front elevational view of the design article;

FIG. 4 is a side elevational view of the clothes support, the other side elevational view being identical; and

FIG. 5 is a rear elevational view of the design article.

I claim:

The ornamental design for a wheeled clothes support, as shown and described.
